UNITED STATES PATENT OFFICE.

HENRY W. O'DOWD, OF JERSEY CITY, NEW JERSEY, ASSIGNOR TO WILLIAM M. CRANE COMPANY, A CORPORATION OF NEW YORK.

SAD-IRON.

1,244,887.

Specification of Letters Patent. Patented Oct. 30, 1917.

Application filed October 18, 1913. Serial No. 795,824.

To all whom it may concern:

Be it known that I, HENRY W. O'Dowd, a citizen of the United States, and a resident of Jersey City, county of Hudson, and 5 State of New Jersey, have made certain new and useful Improvements in Sad-Irons, of which the following is a specification.

This invention relates to sad irons, and more particularly to sad irons provided with 10 internal combustion chambers.

Objects of the invention are to provide an improved construction of the character referred to, which shall be highly efficient in operation, and, at the same time, simple, 15 durable, and economical in construction.

These and other objects of the invention will in part be obvious and in part be more fully described.

The invention consists in the novel parts, 20 improvements, combinations and features of construction herein shown and described.

In the accompanying drawings which are referred to herein and form part hereof is illustrated an embodiment of the invention, 25 the same serving in connection with the description herein to explain the principles of the invention.

Of the drawings:

Figure 1 is a perspective view of a sad 30 iron constructed in accordance with the invention;

Fig. 2 is a longitudinal, vertical central section of the same;

Fig. 3 is a transverse, vertical section of 35 the same taken on line 3—3 of Fig. 2;

Fig. 4 is a plan view taken on the line 4—4 of Fig. 3, parts being broken away and the baffle being removed; and

Fig. 5 is a perspective view of a detail.

40 A sad iron constructed in accordance with one feature of the invention includes in combination a hollow body, the base thereof having a recess extending longitudinally in and midway thereof, a burner arranged in 45 said recess, and said burner having on each side horizontally directed perforations formed therein above the top face of said base.

According to another feature of the invention, the top face of the base slopes upwardly at its outer portions, and the horizontally directed perforations are formed 50 in the burner above the said top face of the base. In one embodiment of this feature of 55 the invention, said burner divides said re-

cess into longitudinal chambers which supply the burner with air, communicating for this purpose with air ports formed in the said base.

According to other features of the invention air ports are formed in the toe and rear wall of the iron adjacent the burner and preferably above the horizontal plane thereof, and a baffle is arranged above the burner. In one embodiment of these features of the invention the forward portion of said baffle inclines upwardly.

Referring now in detail to the embodiment of the invention illustrated in the drawings, there is shown a sad iron comprising a casing 8 of the usual form with a detachable handle 9.

It is important that the entire bottom of a sad iron should be thoroughly heated. For this purpose, therefore, and preferably as shown, a recess is formed longitudinally in and midway of the base 10, of said casing, extending, as shown, from the rear wall 11 to the toe 12. In this recess is arranged a burner 14, to which a further reference will be made, and which divides the recess into two compartments or chambers, 15, 16, see Fig. 3, to which chambers air is supplied through air ports 17, which are also formed in the base, extending transversely thereof, and which communicate with said chambers.

Additional air is supplied through ports 19 formed in the rear wall 11 of the casing, and as these ports communicate through the chambers 15, 16, with the ports 17, and particularly on account of their communication with the most forward of said ports 17, it will be noted that the air in the chambers 15, 16, can be quickly replenished and particularly when the iron is moved forward and back.

While the said chambers 15 and 16 may be formed in any suitable shape and size, in order to insure a proper supply of air and further to provide for the heating of the air before arriving at the place of combustion the chambers are extended laterally in the base, see Fig. 3, the top surface of which forms overhanging ledges 21. As shown, also the cylindrical shape of the burner increases the capacity of these air chambers and facilitates the approach of the air to the jet openings or places of combustion hereinafter referred to.

In order that the front or toe of the iron 110

may be heated equally with the main portion of the iron, the recess in the base of the iron, forming the chambers 15 and 16, is tapered at its forward end in correspondence 5 with the tapering of the casing 8.

The heating member, as said, comprises a burner 14, preferably of cylindrical shape, among other reasons, to increase the capacity of the chambers 15, 16, and to facilitate 10 the approach of the air to the jet openings presently to be described. The burner likewise is tapered to correspond with the tapering recess in which it is located, and in this manner sufficient space is provided 15 for proper combustion and consequent heating of the toe, thus overcoming a defect in the constructions of the art. The burner may be provided with the usual air mixing tube, not shown.

20 Further to insure efficient heating of the base, the burner is provided with horizontally directed perforations 22 formed in each of its sides, as shown, about midway thereof, and slightly above the top surface of the 25 base. Said top surface, while generally horizontal, is upwardly inclined at its outer portions, see Fig. 3, being divided by said recess into two portions 23 and 24. It will be seen that by reason of this construction the 30 flames of the burner are projected nearly horizontally at a slight distance above the said portions 23, 24 of the top surface of the base, and at their ends will curl upwardly and thus the heated products of 35 combustion will be used to the best advantage in heating the base of the iron.

At a suitable distance above the burner is arranged a baffle 25 secured in place in any suitable manner, as by screw 26, to the top 40 27. Preferably, and as shown, the baffle comprises a bottom 28, vertical sides 29, and rear wall 30, and a top plate 31, between which plate and outwardly extending flanges 33 of the walls 29 is preferably 45 placed a sheet 34 of insulating material, as asbestos. The forward portion 36 of the bottom 28 is inclined upwardly to facilitate the disposition of the heated products of combustion, which, passing upwardly along 50 said inclined portion and also in the space between the sides 29 of the baffle and the walls of the casing, see Fig. 3, escape through the vents 38 formed in the upper sides of the casing. The baffle thus forms 55 an insulating chamber, preventing the top of the iron from becoming too hot. It will be noted, see Fig. 3, that the bottom of the baffle thus constitutes the top of a chamber, in which the burner is partly located, and 60 thus concentrates the action of the heated products of combustion upon the base 10 of the iron.

Another feature of the invention relates to means for assisting in the passage of the 65 heated products of combustion from the said

chamber above the burner formed in part by the bottom of the baffle. As shown, see Figs. 1 and 2, ports 40 of large size are formed in the toe of the iron, and ports 41, also of large size, are formed in the rear wall 70 11, these front and rear ports being in communication with the said chamber and with each other. The movement of the iron back and forth will cause a sufficient draft to keep the iron at a proper temperature and 75 properly to regulate the escape of the heated products of combustion.

It will be seen that a sad iron constructed in accordance with the invention carries out the objects of the invention, while possessing 80 other advantages, which will be apparent to those skilled in the art.

The invention in its broader aspects is not limited to the precise construction shown and described, nor to any particular construction by which the same has been or may be carried into effect, as many changes may be made in the details without departing from the main principles of the invention or sacrificing its chief advantages. 90

I claim:

1. A sad iron including in combination, a hollow body, a burner in the lower portion thereof, a baffle located in said body above the burner, vents formed in the upper walls 95 of the iron and air ports formed in the toe and rear wall adjacent the burner and between the burner and said vents.

2. A sad iron including in combination, a hollow body, the top face of the base thereof sloping upwardly at its outward portions, a recess extending longitudinally in said base, and a burner arranged in said recess, said burner having horizontally directed perforations formed therein above said top face 105 of said base.

3. A sad iron including in combination, a hollow body, the top face of the base thereof sloping upwardly at its outward portions, a recess extending longitudinally in and 110 midway of said base, and a burner arranged in said recess, said burner having horizontally directed perforations formed therein above said top face of said base.

4. A sad iron including in combination, a hollow body, the top face of the base thereof sloping upwardly at its outward portions, a recess extending longitudinally in and 115 midway of said base, a burner arranged in said recess, said burner having horizontally directed perforations formed therein above said top face of said base, and air ports in said base communicating with said recess.

5. A sad iron including in combination, a hollow body, the base thereof having a 125 tapering recess, and a tapering burner arranged in said recess.

6. A sad iron including in combination, a hollow body, the base thereof having a tapering recess, extending longitudinally 130

and midway therein, and a tapering burner arranged in said recess.

7. A sad iron including in combination, a hollow body, the base thereof having a recess tapering at one end and extending longitudinally and midway therein, and a burner tapering at one end and arranged in said recess.

10 8. A sad iron including in combination, a hollow body, the base thereof having a recess extending longitudinally and midway therein, and a burner arranged in said recess, said recess and said burner tapering at the respective front ends.

15 9. A sad iron including in combination, a hollow body, the base thereof having a tapering recess, a tapering burner arranged in said recess, and horizontally directed perforations formed in said burner above the 20 top surface of said base.

10 10. A sad iron including in combination, a hollow body, the base thereof having a tapering recess, a tapering burner arranged in said recess, and horizontally directed perforations formed in each side of said burner above the top surface of said base.

25 11. A sad iron including in combination, a hollow body, the base thereof having a tapering recess, a tapering burner arranged in said recess, horizontally directed perforations formed in said burner above the top surface of said base, and air ports in said base communicating with said recess.

35 12. A sad iron including in combination, a hollow body, the base thereof having a recess therein, a burner arranged in said recess and dividing the same into chambers, and the roof of each said chamber having its edge adjacent the burner spaced apart therefrom.

40 13. A sad iron including in combination, a hollow body, the base thereof having a recess therein, said recess having overhanging ledges, and burner arranged in said recess and spaced apart from said ledges and dividing said recess into chambers.

14. A sad iron including in combination, a hollow body, the base thereof having a recess therein, said recess having overhang-

50 ing ledges, and a burner arranged in said recess and spaced apart from said ledges and dividing said recess into chambers, and horizontally directed perforations formed in each side of said burner above the top surface of said base.

55 15. A sad iron including in combination, a hollow body, the base thereof having a recess therein, said recess having overhanging ledges, and a burner arranged in said recess and spaced apart from said ledges and dividing said recess into chambers, and horizontally directed perforations formed in each side of said burner above the top surface of said base, and air ports in said base communicating with said recess.

60 16. A sad iron including in combination, a hollow body, a burner arranged on said base longitudinally and mid-way thereof, horizontally directed perforations formed in each side of said burner, and a pair of air 70 supply chambers arranged one on each side of said burner and beneath said perforations.

65 17. A sad iron including in combination, a hollow body, the top face of the base thereof sloping upwardly at its outward portions, a recess extending longitudinally in and midway of said base, a burner arranged in said recess, said burner having perforations formed therein above said top face of said base, and air ports in said base communicating with said recess.

75 18. A sad iron including in combination, a hollow body, and a burner in the lower portion thereof, a baffle located in said body above the burner and air ports formed in the toe and rear wall adjacent the burner in substantially the same horizontal plane and above the horizontal plane of said burner, whereby circulation may be established between the burner and baffle.

80 85 In testimony whereof, I have signed my name to this specification, in the presence of two subscribing witnesses.

HENRY W. O'DOWD.
